RECORD SYSTEM FOR CONTROLLING PROGRESSIVE DISTRIBUTION OF COUPONS

John F. Briskey, 412 Empire Bldg., Birmingham 3, Ala.
Filed Oct. 17, 1955, Ser. No. 540,793

3 Claims. (Cl. 283—63)

This invention relates to a record system for controlling progressive distribution of coupons or a consumers cooperative merchandising system. It has for its main objects to create a desire on the part of the buying public to trade with retail merchants; to create means for the buying public to carry on the system without any effort on the part of the merchants; to provide profit for the buying public in a novel and exciting way and stay within the protection of all laws; and have a mechanical structure consisting of the use of coupon books with interlocking parts and identifying numbers.

Other objects and advantages will appear from the drawings and description.

By referring generally to the drawings, a part of this application, it will be observed that FIG. 1 is a plan view of the front cover of a V-star thrift book used in the system; FIG. 2 is a plan view of the back cover of the book shown in FIG. 1; FIG. 3 is a plan view of the back face of three identical inserts that comprise the last three sheets of a V-star thrift book; FIG. 4 is a plan view of the front face of the inserts shown by FIG. 3; and FIG. 5 is a plan view of a coupon as used in the thrift book.

Similar reference numerals refer to similar parts throughout the several views.

Referring to the drawings in detail it will be seen that the system comprises a thrift book 1 having a number 100-B. It contains one hundred coupons 2 worth 25¢ each and cost the purchaser \$5.00. The back 3 of the book 1 and \$10.00 entitles the purchaser to a unit of three additional books from a sponsor having the number 100-B, the purchaser being designated as the first assistant and having the same number 100-B. The back 3 of the book serves as a coupon that gives the purchaser the right to purchase the three additional books at the reduced price of \$10.00. The back of the book is also numbered the same number as the front. It also has four oblong openings 4 in its lower half. Attached removably to and under the back cover is a label 5 with four numerals 1, 2, 3 and 4 that are visible through the openings 4. There are two additional similar labels and each is carbonized in the space 7 for use in tracing the numbers 1, 2, 3 and 4 onto the two additional labels.

In operation the system is carried through as follows: an individual acquires a V-star thrift book. The inside of the front cover explains how the book is to be used. The back of the book serves as a coupon that gives a person the privilege of acquiring three additional books at a reduced cost. He may retain the books for his own use or sell them at \$5.00 each. The back cover has the same number printed on it as the front cover. It also has four openings in its lower part. Attached to and under the back cover is a label from another book with four numbers that are visible through the said four openings. Directly under the back cover there are three labels as the last three pages of the book which are identically numbered at the top with four additional numbers on each. One of these labels is removably attached to the back cover. These labels are used according to directions as indicated by 8. If the purchaser elects to acquire three additional books with the back cover of a V-star thrift book, he plainly prints his name and address on the back cover as indicated at 9. He tears it off on

2

perforated line at top and gives it to a sponsor who is identified by being the bearer of a V-star thrift book that bears the number that is in the opening at the bottom of the back cover that is turned in, along with \$10.00, and receives a unit of three V-star thrift books. If the owner of the three books obtained in the unit wishes to dispose of one or all, he tears one pre-numbered label from the book that he used the back cover of to obtain the unit, slips it up under the back cover of the new book to where the numbers are centered in the openings, attach removably by pin or clip and then trace the numbers showing in the openings which will be transposed by the carbonized spaces on the labels.

In other words the plan works as follows: a first party buys one V-star book for \$5.00 containing 100 V-star coupons. When shopping with merchants displaying the V-star emblem the first party presents one of the coupons at the time of making a \$4.00 purchase and the merchant will give the first party 25¢ cash. For each additional \$4.00 purchase an additional payment of 25¢ will be made. With the back cover of the book purchased the first party is eligible to purchase from one of the participating merchants a bonus package of three books for \$10.00, each containing 100 coupons redeemable at 25¢ each. The first party may keep the books and use same or sell same at \$5.00 each. The first party V-star book purchased has a number. Each book has its own number. When the first party uses the back cover of the first book purchased to purchase three additional books the merchant will stamp his trade name, address and date on it, then the first party returns this cover to the party from whom the book was purchased. The party whose number appears in the bottom window or opening of the cover is eligible for either \$8.00 in merchandise or \$6.00 cash. Thus by returning the back cover each time to the party from whom the book was purchased, it will work back to that individual party as means to go to the store whose name is stamped on this cover and receive the award. The said work back results from the following procedure. When the three books are purchased instructions on each will show where and how to imprint the purchaser's number in each. The purchaser's number will as each book proceeds, work to the bottom of the page and it will be the purchaser's turn to collect merchandise or cash. The purchaser must keep in mind that the party to whom one of the books is sold with the purchaser's number on the back can use the back to purchase three additional books. The numbers of the purchaser and the number of the new buyer will appear on the three new books. The number of the original first party as purchaser on the original book progresses downward until as many as 81 V-star books may appear with the number of the original first party purchaser on each book. This cycle continues and each time the number of the first party purchaser appears at the bottom the first party purchaser will make a profit. As a result it is possible for the first party purchaser in each cycle to earn up to \$648.00 in merchandise or \$486.00 cash.

From the foregoing it will appear that the numbers used increase in units progressively and sponsors become designated as the system is carried along. To begin the system a book may be obtained from any source, such as a distributor in control of the system in certain territory, or from a merchant displaying a notice that he accepts V-star coupons from customers at 25¢ each based on goods purchased in \$4.00 units.

While I have shown and described the preferred embodiment of my invention, I do not wish to limit same to the exact and precise details of the records and instructions used, but reserve the right to make all modifications

tions and changes so long as they remain within the scope of the invention and the following claims.

Having described my invention I claim.

1. A record system for controlling progressive distribution of coupons comprising a book having a plurality of detachable coupons with a money value printed on each one, and a front cover with the title V-star thrift book and the outline of a star printed thereon, and its price and savings value printed thereon, and a number printed thereon; and a back with instructions for its use printed thereon, said back being numbered the same number as the front and having four oblong similar openings formed in its lower portions, and printed under the upper opening the words first assistant, and under the next downward opening the words second assistant, and under the next downward opening the words third assistant, and under the fourth opening the word sponsor; said book back having a label attached thereto with instructions for its use and places for numbers to show through said oblong openings when placed as instructed by printing on its face two similar pages as labels in the book, each of said three pages as labels having a carbonized portion on its back for tracing and transferring numbers by manual means through the said oblong openings, each of said three pages as labels being means in connection with a back cover of a book for obtaining a unit of three additional books at a special price from a sponsor.

2. A record system for controlling progressive distribution of coupons having money value comprising a book containing a plurality of money value coupons, three last pages of the book being numbered and being means for obtaining additional books at a special price, the back of the book having four oblong openings formed therein, said openings being adapted for tracing numbers therethrough, said last three pages being labels for use in obtaining additional books at a reduced price, said labels having carbonized portions on their backs for transposing numbers by manual means of tracing through said openings, said parts being numbered progressively as identifying means with reference to the books and their use.

3. A book record system of the character described for

controlling progressive distribution of coupons, said book having a plurality of pages therein comprising a plurality of detachable coupons with each having a number and money value printed thereon, said book having a front cover with the title V-star thrift book and the outline of a star printed thereon, and said cover having printed thereon the following price, \$5.00, cash saving value of this book \$25.00, said cover having a number printed thereon, said book having a back, this back being numbered the same number as on the front cover, said back having four oblong similar openings or windows formed therein and positioned apart and parallel with each other, the opening in the center portion of the back having printed adjacent an edge of the opening the words first assistant, and printed adjacent the next opening the words second assistant, and adjacent the next opening the words third assistant, and adjacent the next opening the word sponsor; said book having attached removably for use under its back cover three identical labels for separate use, each of said labels being perforated at its top and bottom portions and having printed thereon instructions for its use as follows, notice, this label is to be pinned under the back cover of one of the V-star thrift books issued for the back cover of this thrift book Number 1164 C, No. second assistant, No. third assistant, No. sponsor, bend up on perforated line, slip up under back cover of new book to where numbers are centered in four openings, pin in place and trace numbers; each of said labels have a carbonized portion on its back adapted for tracing and transferring numbers by manual means through the said oblong openings, each of said three labels being means in combination with a back cover of a V-star thrift book for obtaining a unit of three additional books at a special price from a store showing the V-star emblem.
